W. A. RINGLER

VISIBLE INDEX

Filed March 10, 1922

UNITED STATES PATENT OFFICE.

WILLIAM A. RINGLER, OF PHILADELPHIA, PENNSYLVANIA, ASSIGNOR TO THE GLOBE-WERNICKE COMPANY, A CORPORATION OF OHIO.

VISIBLE INDEX.

Application filed March 10, 1922. Serial No. 542,573.

To all whom it may concern:

Be it known that I, WILLIAM A. RINGLER, a citizen of the United States, residing at Philadelphia, in the county of Philadelphia and State of Pennsylvania, have invented certain new and useful Improvements in Visible Indexes, of which the following is a full, clear, and exact description.

This invention relates to card index devices of the so-called visible index type, in which a series of index cards are supported in a frame, with the free edges of the cards projecting one beyond the other so as to leave a narrow portion of a surface of each card exposed along its free edge, which portion is adapted to carry the name, address, identification number, or other suitable information or data in a position to be always visible.

An object of the invention is to provide improved means for supporting the cards in position, which will enable the rapid insertion or withdrawal of a card at will, anywhere in the index, without removal or rearrangement of the other cards; which will permit of ready access to both sides of any card for the purpose of obtaining information therefrom or entering additional information thereon, without removing the card from the frame; which prevents the cards from falling out or becoming disarranged when the frame is shifted to different positions; with which an index card may be quickly removed from its carrier or applied thereto, without removing the carrier from the supporting means; and which is simple, compact, convenient and inexpensive. A further object is to provide an improved index card carrier which may be inexpensively manufactured from sheet material. A further object is to provide an improved index card which may be flexed adjacent to its attached edge without danger of breakage or the formation of sharp bends therein. Other objects and advantages will be apparent from the following description of an embodiment of the invention, and the novel features will be particularly pointed out in claims.

In the accompanying drawing:

Fig. 1 is a plan of an index device constructed in accordance with the invention;

Fig. 2 is a sectional elevation of a card in its carrier;

Fig. 3 is a fragmentary plan of a card and its carrier, in the relative positions which they assume when the card is being inserted into the carrier;

Fig. 4 is an edge view of a carrier;

Fig. 5 is a side elevation of the index card when flexed;

Fig. 6 is a plan view of a modified type of card carrier;

Fig. 7 is an edge view of the same; and

Fig. 8 is a cross sectional elevation of the same.

In the embodiment illustrated in Figs. 1 to 5 a frame 1, which may conveniently be formed of sheet metal, is provided on opposite sides with inturned peripheral edge flanges 2 which extend parallel with the face of the frame, so as to provide internal peripheral grooves. The grooves along opposite sides of the frame are utilized as guideways for the card carriers 3. The card carriers are each formed of a flat strip of sheet material, which may conveniently be of sheet metal, having the ends looped and doubled back thereon to form enlarged terminals 4, which slide in the guideways of the frame, with the flat face of the carrier parallel with the face of the frame. The carriers normally abut against one another, edge to edge, and the enlarged terminals 4 prevent one carrier from overlapping the other when the frame is tipped or carried about.

The side edges of each carrier are provided with tongues 5 and 6 which are doubled back upon the same face of the strip to form therewith grooves extending lengthwise of the carrier, the grooves opening toward one another, and the edges of the tongues being preferably spaced apart in the direction of the width of the face of the carrier. An edge portion 7 of an index card 8 is doubled back upon itself to form an offset or folded edge portion which is adapted to be inserted into the grooves of the carrier and anchor the index card therein. One groove of each carrier, such as that formed by the tongue

6, has a greater width between the side walls of the groove than the corresponding width of the opposite groove of the same strip. The free edge of the folded edge 7 of the index card is inserted into the groove having the narrower width, and the doubled back edge of the card is inserted into the groove having the greater width as shown clearly in Figure 2. With this arrangement, 10 the cards may lie substantially flat over the tongue 5. One of the tongues, such as 5, which forms one of the grooves is extended nearer the ends of the carrier than the other tongue which forms the opposite groove of 15 the same carrier, so as to facilitate the insertion therein of the offset or angular end of the index card. A holding member 9 is provided with extensions 10 which project into the guideways in which the carriers 20 slide, so as to secure the holding member to the frame with provision for adjustment along the same in the direction of adjustment of the card carriers. The holding member is preferably a flat strip of sheet 25 metal having a pair of slots or apertures 11 and 12 therein, extending lengthwise of the member and spaced apart in the direction of adjustment in the guideways. A flexible strip 13 of fabric or spring steel, preferably the latter, is anchored at its ends to 30 the ends of the frame and extends lengthwise along the face of the frame beneath the carriers. The strip 13 passes through both of the apertures 11 and 12, preferably entering and leaving the member from the under 35 face thereof, so that as the holding member is adjusted along the frame, it will be frictionally held in any adjusted position. The holding member is shifted along the guideways to abut the carriers in the frame, and 40 hold the latter together and against one end of the frame so as to prevent separation of the carriers sufficiently to permit of the assumption by any carrier of a diagonal position which would allow it to drop out of the frame. The holding member is also provided with an aperture 14 with one edge offset which provides a ledge for manual engagement when the holding member is shifted 45 along the guideways of the frame. The face of the frame against which the carriers abut is provided with a pair of elevated ribs 15, which extend lengthwise of the frame, so as to form rails in contact with the under 50 face of the carriers and prevent inward flexure of the same and also reduce sliding friction during movement of the carriers and holding member along the frame.

Each index card is also preferably provided adjacent to the folded edge portion by 60 which it is attached to the carrier, with a row of spaced apertures 16 extending parallel with the offset edge for facilitating the flexure of the card with respect to its at-

tached edge. Each index card is also preferably provided in a surface adjacent to the folded edge, and preferably between the spaced apertures 16, with a plurality of scorings 17 which extend parallel to the attached edge. When the body of the card is flexed 65 with respect to its attached edge, as shown in Figure 5, the scorings will permit bending of the card at a plurality of points, each of which points of flexure is at a scoring, so that the total length of flexure is divided up 70 among the strips between the scorings, and thus danger of sharp bends or breakage along the lines of flexure is largely eliminated.

In the use of the device, the frame is provided with a number of card carriers 3 which are arranged in the guideways and each is provided with an index card, the carriers being normally held together at one end of the frame by means of the holding member 9. When an index card is inserted into its carrier, it is not necessary to first remove the carrier from the frame. The card is brought into the position shown in Fig. 3, with respect to the grooves of the carrier, and 80 the free edge of the offset or bent edge of the card is inserted into the end of the groove formed by the tongue 5, and then shifted edgewise of the index card to bring the doubled-back edge of the card into the 85 end of the groove formed by the tongue 6, the movement being continued until the card is brought centrally of the carrier, an intermediate position being shown in dotted lines in Figure 1. To remove a card from its carrier, it is merely necessary to flex an end of the card sufficiently to clear the adjacent side flange 2, and then the card may be pulled edgewise of itself from the carrier. If it is desired to insert additional carriers 90 between the carriers already in the frame, it is merely necessary to shift the holding member away from the other carriers, and then separate the carriers at the point where the insertion is to be made. An additional 100 carrier is then placed in a diagonal position with respect to the frame and rotated in a direction to carry the terminal ends 4 beneath the flanges 2, after which the carriers may be shifted together. It will be obvious 105 that with this arrangement the frame may be disposed with the cards extending in any desired direction and the cards may be easily flexed to expose either face for the addition of information thereto, or for an 110 inspection. The cards will remain in flexed positions with either face exposed, owing to the reduction in the resiliency of the cards along the line of flexure caused by the apertures, scorings, or both.

In Figs. 6, 7 and 8 a slightly modified type of card carrier is shown, the strip 18 of sheet metal being rotatably mounted upon

the intermediate portion of a wire 19 having terminals 20 bent angularly thereto in the same plane with one another which slide in the guideways of the frame. The wire may 5 be offset slightly as at 21 where it leaves the strip 18 so as to hold the strip against sliding movement along the wire. The cards may thus be rotated on the wire to bring either face into full view and will lie flat in either 10 extreme position.

It will be obvious that various changes in the details and arrangements of parts herein described and illustrated for the purpose of explaining the nature of the invention, may 15 be made by those skilled in the art within the principle and scope of the invention.

I claim:

1. In a visible index device, a card carrier comprising a strip having card-receiving 20 grooves along opposite edges of a face, the grooves opening toward one another, one of said grooves extending nearer an end of the strip than the other groove to facilitate the insertion of the edge of a card in said 25 grooves.

2. In a visible index device, a card carrier, and an index card attached along one edge to said carrier, said card having adjacent to its attached edge and interiorly 30 therefrom a row of spaced apertures to facilitate the flexure of the card with respect to the carrier.

3. In a visible index device, a card carrier, and an index card attached along one 35 edge to said carrier, said card having adjacent to its attached edge a row of spaced apertures to facilitate the flexure of the card with respect to the carrier, the apertures being connected by a plurality of scorings to 40 also facilitate flexure of the card without breaking or causing sharp bends therein.

4. In a visible index device, a card carrier comprising a strip having opposing 45 card-receiving grooves upon one face thereof of opening toward one another, an outer wall of one of the grooves terminating at a greater distance from the adjacent end of the strip than the corresponding adjacent 50 wall of the opposite groove in order to facilitate the insertion into said grooves, end- wise, of an angular edge of an index element.

5. An index card having adjacent to an 55 edge, by which it may be mounted, parallel thereto and interiorly therefrom a row of spaced apertures to facilitate flexure of the body of the card with respect to the said edge.

6. The index card as set forth in claim 5 60 in which a surface of the card is provided with a plurality of spaced scorings between the apertures and parallel to the adjacent edge to also facilitate flexure of the body of the card without the formation of sharp

bends or breakage of the card along the line 65 of flexure.

7. In a visible index device, a frame having guides along opposite edges, a plurality of index card carriers cooperating with said guides for sliding movement along the 70 frame, a holding member also cooperating with said guides for sliding movement along the frame, a flexible strip connected to the ends of the frame and having an engagement with said member whereby the member may 75 be adjusted along the frame to hold the card carriers together and be held in adjusted positions.

8. In a visible index device, a frame having guides along opposite edges, a plurality 80 of index card carriers cooperating with said guides for sliding movement along the frame, a holding member also cooperating with said guides for sliding movement along the frame, a flexible strip connected to the ends of the frame and having frictional engagement with said member, whereby the member may be adjusted along the frame to hold the card carriers together and be held 85 in adjusted positions.

9. In a visible index device, a frame having guides along opposite edges, a plurality of index card carriers cooperating with said guides for sliding movement along the 90 frame, a holding member also cooperating with said guides for sliding movement along the frame, a flexible strip connected to the ends of the frame and passing through 95 spaced apertures in said member whereby the member may be adjusted along the frame 100 to hold the card carriers together and be held in adjusted positions.

10. In a visible index device, an index card carrier comprising a strip of sheet material having flanged edges forming grooves 105 extending lengthwise of the strip, spaced from and opening towards one another, one of said flanged edges extending nearer an end of the strip than the corresponding end of the other edge whereby the insertion of 110 an angular end of an index card into said grooves is facilitated.

11. In a visible index device, an index card carrier having grooves on one face extending lengthwise thereof and opening towards one another, one of said grooves at 115 one end extending further towards the end than the other groove.

12. In a visible index device, a member adapted to slide between spaced guides and having an intermediate wire portion, a card holder of sheet metal with portions bent thereon to form card-attaching means and also embrace the wire portion to form a 120 hinge connection thereto.

13. In a visible index device, a member adapted to slide between spaced guides, a card holder articulately connected thereto so 125

as to swing to expose to view either face thereof, said holder having opposed spaced grooves upon one face for detachably receiving the bent-over edge of an index card.

5 14. In a visible index device, a follower block of sheet metal having at its forward end lateral extensions for travel in guide-

ways, and having adjacent its rear end an integral deflected portion to form a grasping portion, the body part having therein a 10 plurality of slots for receiving a tape.

In witness whereof, I hereunto subscribe my signature.

WILLIAM A. RINGLER.
